POWDER DISPENSING BOX

William J. Bauer, New York, N. Y., assignor to
Robert Lederfeind, New York, N. Y.

Application December 5, 1933, Serial No. 700,950

4 Claims. (Cl. 132—82)

The invention relates to powder cases or boxes for retaining a powder or similar material in loose form together with a puff or similar element designed to apply the powder material.

5 It has for an object, in a box of this character, the provision of means whereby the retained powder, as the supply thereof becomes depleted, remains readily accessible for application to the puff without requiring shaking or other manipulation 10 of the container as a whole, and without scattering or waste of the powder.

A further object of the invention resides in the provision of a box of the aforesaid nature which may be maintained in sanitary condition and 15 the powder sealed when the box is not in use.

A still further object of the invention resides in the provision of a loader or refill member particularly suitable for use with more or less elaborate and expensive containers which it is not desired to discard when the initial charge of powder is exhausted. Another object of the invention is to afford a loader element of this type of an elastic or resilient material which, while securing the powder against scattering, will yield under 25 pressure applied thereto by the puff element for discharging powder thereon, and be collapsible more or less under its own weight to conform to the receding powder level therein, said powder normally serving to distend the said loader element. 30

A still further object of the invention resides in the provision of means for sealing the loader element against the entrance of moisture when the same is not in use, or for preventing spilling 35 of the powder when it is desired to transport the loader element.

In the accompanying drawing, which illustrates a preferred embodiment of the invention, Fig. 1 illustrates the novel powder box in plan view, with the cover removed.

40 Fig. 2 is a vertical section therethrough.

Fig. 3 is a horizontal section through the box taken on the line 3—3, Fig. 2 of the drawing.

45 Fig. 4 is a vertical section through the powder box, with cover removed, and illustrates the loader element in partly collapsed condition.

50 Referring to the drawing, 10 designates a casing of suitable shape and size and designed to afford a compartment within which is to be mounted a loader element 11 to substantially occupy the lower portion of the container or box 10, said element resting upon the bottom thereof as shown in Figs. 2 and 4.

55 This loader element consists of an elastic or resilient material, such as rubber, which may read-

ily be shaped, as by dipping a form of the desired contour into liquid rubber, to conform to the interior of the box 10 as well as to provide the series of circumferential corrugations 12 forming of the said element a bellows or like collapsible member. The powder 13 for use is filled into the said loader element 11 through an opening 14 provided in its top, which opening may be arranged to be closed by a removable disk 15 having perforations 16 designed, for controlling the outflow 10 of the powder, to register with the perforations 17 of a rotatable slide 18 pivoted to the disk 15 as at its center 19. The powder 13 within the loader 11 serves to distend the same and may be readily sealed therein by turning the slide 18, 15 through a tab 20 attached thereto, to a position to avoid registry of the respective sets of perforations 16 and 17, as when the box is not in use or when it is desired to transport the loaded box or to store the loader element as refills. 20

The cooperating disks 15 and 18 may be of any suitable material, such as celluloid, hard rubber or metal; and the former disk is arranged to be frictionally held at its circumference within the annular recess 21 formed by doubling over 25 the inner edge of the top of the loader element, it being desirable to this end to also roughen, as by knurling, the circumference of said disk. This doubled-over edge will be stretched over the circumference of the said disk 15 to hold the 30 same securely under the natural resiliency of the loader element material, which resiliency will tend also to direct the powder toward the outlet opening 14 in the top of the element as well as conforming the shape of the element more 35 or less to the quantity of powder retained therein. When the two sets of perforations are in registry, the powder may be received upon a puff 22 or like member by pressing the same downwardly upon the top of the loader element. 40

If it be desired to refill a loader element, the sealing disks 15 and 18 may readily be separated from the body of the element by stretching the edge or recess 21; and, similarly, the said disks 45 may conveniently be replaced when the powder has been loaded into the said element.

By combining an outer container with a loader element of the nature set forth, refilling of the same is readily provided for, and not only is the 50 powder readily and conveniently accessible at all times but it is sanitarily maintained and may be dispensed with a minimum of waste and without undue scattering. As the supply becomes depleted, the element 11 will tend to collapse, as in- 55

dicated in Fig. 4, to conform to the diminished contents which will be thus always accessible to the puff pressed over the outlet 14.

I claim:

- 5 1. A loader element for powder boxes adapted to rest upon the bottom thereof and free at the opposite end, said element comprising a seamless, one-piece elastic rubber receptacle of a thickness sufficient to afford a self-sustaining powder
- 10 10 receptacle and having a succession of vertically disposed circumferential folds whereby the element may be collapsed, to follow the contents as the same are depleted, by exerting pressure upon the top thereof which is provided with a centrally disposed outlet opening, and means to seal said opening.
- 15 2. A loader element for powder boxes adapted to rest upon the bottom thereof and free at the opposite end, said element comprising a seamless, one-piece elastic rubber receptacle of a thickness sufficient to afford a self-sustaining powder receptacle and having a succession of vertically disposed circumferential folds whereby the element may be collapsed, to follow the contents as the same are depleted, by exerting pressure upon the top thereof which is provided with a centrally disposed outlet opening, and the said receptacle having a top inturned flange extending beyond the inner edges of the folds to afford a centrally disposed outlet opening, and means to seal said opening.
- 20 3. A loader element for powder boxes adapted to rest upon the bottom thereof and free at the opposite end, said element comprising a seamless, one-piece elastic rubber receptacle of a thickness sufficient to afford a self-sustaining powder receptacle and having a succession of vertically disposed circumferential folds whereby the element may be collapsed, to follow the contents as the same are depleted, by exerting pressure upon the top thereof which is provided with a centrally disposed outlet opening, and means to seal said opening.
- 25 4. A loader element for powder boxes adapted to rest upon the bottom thereof and free at the opposite end, said element comprising a seamless, one-piece elastic rubber receptacle of a thickness sufficient to afford a self-sustaining powder receptacle and having a succession of vertically disposed circumferential folds whereby the element may be collapsed, to follow the contents as the same are depleted, by exerting pressure upon the top thereof which is provided with a centrally disposed outlet opening, and the said receptacle having a top inturned flange extending beyond the inner edges of the folds to afford a centrally disposed outlet opening, the material about the edge of the opening being doubled upon itself to afford an annular recess, a perforated disk fitting within said recess and removably retained therein under the inherent resiliency of the rubber, and a slide member rotatably mounted upon the disk having perforations adapted for registry with the perforations of the said perforated retained disk.

tically disposed circumferential folds whereby the element may be collapsed, to follow the contents as the same are depleted, by exerting pressure upon the top thereof which is provided with a centrally disposed outlet opening, and the said receptacle having a top inturned flange extending beyond the inner edges of the folds to afford a centrally disposed outlet opening, the material about the edge of the opening being doubled upon itself to afford an annular recess, and a 10 perforated disk fitting within said recess and removably retained therein under the inherent resiliency of the rubber.

4. A loader element for powder boxes adapted to rest upon the bottom thereof and free at the opposite end, said element comprising a seamless, one-piece elastic rubber receptacle of a thickness sufficient to afford a self-sustaining powder receptacle and having a succession of vertically disposed circumferential folds whereby the element may be collapsed, to follow the contents as the same are depleted, by exerting pressure upon the top thereof which is provided with a centrally disposed outlet opening, and the said receptacle having a top inturned flange extending beyond the inner edges of the folds to afford a centrally disposed outlet opening, the material about the edge of the opening being doubled upon itself to afford an annular recess, a perforated disk fitting within said recess and removably retained therein under the inherent resiliency of the rubber, and a slide member rotatably mounted upon the disk having perforations adapted for registry with the perforations of the said perforated retained disk.

WILLIAM J. BAUER.
